UNITED STATES PATENT OFFICE

2,190,893

INVISIBLE HATPIN

Beatrice T. Symons, Skowhegan, Maine

Application February 16, 1939, Serial No. 256,743

2 Claims. (Cl. 132—68)

The figure is a plan view of an invisible hatpin. This hatpin has two prongs; the longer approximately two and one-half inches in length, is perfectly straight and has a very sharp point. 5 at one end to be inserted through the inner band of a hat; the shorter prong, an extension of the longer by means of a sharp curve at the opposite end from the point, runs parallel to the longer prong and has four short quirks midway of its 10 length. The short prong is approximately one-half inch shorter than the other prong to make it possible to catch the longer prong in the fabric of the hat, if desired; the quirks in the short prong are to hold the hat more securely as this short 15 prong slides through the hair. The short prong has a blunt end.

My hatpin is invisible; is designed to be inserted in the inner band of a hat; it does not alter the lines of crown or brim of hat; it does not injure 20 hat material, no tears or holes; it may be worn singly or in pairs, in back or on the sides of hat,

inserted at any angle, always invisible; it can be used with high hair-dress or low.

I claim:

1. A hatpin having a pair of substantially parallel legs and a substantially U-shaped integral connecting portion at one end thereof, one of said legs being pointed whereby to be insertable in a hat or hat band and the other of said legs having a corrugated portion to be received in the hair, the said pointed leg being of a greater 10 length than the other leg. 5

2. A hatpin having a pair of substantially parallel legs and a substantially U-shaped integral connecting portion at one end thereof, one of said legs being elongated and extending beyond 15 the other leg, said elongated leg being pointed whereby to be insertable in a hat or hat band and the other leg having a relatively blunt end and a corrugated portion to be received in the hair. 20

BEATRICE T. SYMONS.

CERTIFICATE OF CORRECTION.

Patent No. 2,190,893.

February 20, 1940.

BEATRICE T. SYMONS.

It is hereby certified that error appears in the above numbered patent requiring correction as follows: In the drawing, strike out the figure now shown and insert instead the following -

and that the said Letters Patent should be read with this correction therein that the same may conform to the record of the case in the Patent Office.

Signed and sealed this 30th day of April, A. D. 1940.

(Seal)

Henry Van Arsdale,
Acting Commissioner of Patents.
